UNITED STATES PATENT OFFICE.

EMIL PICKART, OF HAMMOND, INDIANA, ASSIGNOR TO FRANK S. BETZ, OF HAMMOND, INDIANA.

JOINT FOR LEG-RESTS.

979,091.

Specification of Letters Patent. Patented Dec. 20, 1910.

Application filed March 28, 1910. Serial No. 552,086.

To all whom it may concern:

Be it known that I, EMIL PICKART, a citizen of the United States of America, and a resident of Hammond, county of Lake, State 5 of Indiana, have invented certain new and useful Improvements in Joints for Leg-Rests, of which the following is a specification.

The main objects of this invention are to 10 provide improved means for supporting the leg rests of surgeons' operating tables; to provide an improved joint whereby a part may be moved longitudinally or rotate about both longitudinal and transverse axes, or 15 describe directly the resultant of all of said movements; to provide an improved locking device in which one movement of a single element will prevent all of said movements; and to provide a compact construction 20 for a joint accomplishing such movements.

A specific construction embodying this invention is illustrated in the accompanying drawings, in which:

25 Figure 1 is a front elevation showing this invention as applied to an operating table for supporting a foot rest. Fig. 2 is a side elevation of the same, omitting the table. Fig. 3 is a section taken on the line 3—3 of 30 Fig. 1. Fig. 4 is a section taken on the line 4—4 of Fig. 1, showing the details of the locking mechanism.

In the construction shown in the drawings, there is a fixed member 1 in the form 35 of a flat plate fastened to the corner 2 of an operating table or chair. A split sleeve 3 is pivoted in an aperture 4 which is located at the center of a slotted arc 5. The pivot 6 is integral with the sleeve 3, and is held in 40 place by means of a cotter pin or key 7. A U-shaped yoke 8 surrounds the split sleeve 3, and its legs extend through the slotted arc 5 and are connected behind the fixed member 1 by means of the foot plate 9, which is 45 secured to the yoke legs by means of a pin 10. The bow of the yoke 8 is tapped and threaded to receive a set screw 11 which has a handle 12. There is an advantage in having broad bearing surfaces between the fixed 50 member 1 and the sleeve 3, and between said member and the plate 9, as the security of the joint depends upon friction.

The locking mechanism consists of the screw 11, which bears directly on the sleeve

3, and, through the resulting tension on the 55 yoke 8, draws the foot plate 9 into frictional contact with the fixed member 1. A round rod or shaft 13 is supported in the sleeve 3, and is gripped by the inner faces of the sleeve 3 through the direct action of the 60 screw 11 on the sleeve. The inner sleeve faces are made yielding by means of a longitudinal slot 14 cut in the sleeve at right angles to the axis of the screw 11. The slot 14 does not entirely separate the sleeve into 65 two parts, and the uncut portion of the sleeve acts as a spring to normally hold the cut portions in original position. The rod 13 carries an adjustable foot rest 15.

In operation, the foot rest is set free for 70 adjustment to any required position by a turn of the lever handle 12. In the construction here shown, a left hand turn to the screw 11 removes the compression between the inner sleeve faces and the rod 13, and 75 at the same time loosens the yoke 8 and removes the compression between the foot plate 9 and the member 1. With one hand, the operator moves the foot rest 15 into any desired position by either the rotation of the 80 rod 13 about its own axis or by sliding the rod 13 through the sleeve or by rotation of the sleeve on its pivot 6, or by a combination of all three movements, and then by a right hand rotation to the lever handle 12 locks all 85 the parts against relative motion.

Although but one specific embodiment of this invention is herein shown, it will be understood that numerous details of the construction shown may be altered or omitted 90 without departing from the spirit of this invention.

I claim:

1. The combination of a member having a slotted arc, a compressible sleeve pivoted thereto, a rod extending through said sleeve and slidable and rotatable therein, a yoke embracing said sleeve and slidably engaging said member at said slotted arc, and a locking element carried by said yoke and arranged to hold all of said parts against relative movement. 95

2. The combination of a member having a slotted arc, a compressible sleeve pivoted at the center of said arc, a rod slidable and rotatable in said sleeve, a yoke embracing said sleeve and extending through said slotted arc, and a locking element carried by said 100 105

yoke for compressing said sleeve upon said rod and locking said sleeve to said first named member.

3. The combination of a member, a sleeve pivotally mounted on said member, a yoke embracing said sleeve and slidably connected to said member, a rod rotatable in said sleeve and axially slid able therein, and means acting between said yoke and sleeve

10 to simultaneously lock said parts to prevent relative movement of said rod and member.

4. The combination of a member, a split sleeve pivotally mounted on said member, a yoke embracing said sleeve and slidably connected to said member, a rod rotatable in said sleeve and axially slid able therein, and means acting between said yoke and sleeve to simultaneously lock said parts to prevent relative movement of said rod and member.

15 5. The combination of a stationary member having a slotted arc, a split sleeve pivoted at the center of said arc, a rod slid able and rotatable in said sleeve, a member movable in said arc and having a part embrac-

20 ing said sleeve, and locking means carried by said member and arranged to compress

said sleeve and secure the same to said stationary member at said slotted arc.

6. The combination of a member, a split sleeve having a transverse pivot journaled in said member, a shaft carried in said sleeve, a yoke embracing said sleeve and member, and a locking screw carried by said yoke and adapted to cause the same to prevent relative motion of all said parts.

35 7. The combination of a member having a pivot aperture and a slotted arc, a split sleeve having an integral pivot journaled in said aperture, a rod carried in said sleeve and adapted to slide and rotate in said sleeve, a yoke embracing said sleeve and slidably engaging said member at said slotted arc, and a locking element carried by said yoke and adapted to prevent the relative motion of all of said parts.

40 45 Signed at Chicago this 23rd day of February 1910.

EMIL PICKART.
